Jack G. Mark, Bayside, N.Y., assignor to Whitney Optical Co., Inc., Woodside, N.Y.

Filed Nov. 19, 1971, Ser. No. 190,472

Term of patent 14 years

Int. Cl. D16—06

U.S. Cl. D57—1 F

FIG. 1 is a front elevational view of a spectacle frame or similar article showing my new design;

FIG. 2 is a top plan view thereof;

FIG. 3 is a side elevational view thereof; and

FIG. 4 is an enlarged cross-sectional view taken on line 4—4 of FIG. 1.

The rear of the frame front has substantially the appearance shown in FIG. 1. The temples are omitted in FIGS. 1 and 2 for convenience of illustration.

I claim:

The ornamental design for a spectacle frame or similar article, as shown and described.
